EFFECTIVE LENGTH ADJUSTING MEANS
FOR APPAREL ELEMENTS

Thomas R. Arden, Baldwin, N. Y., assignor to
Ultral Products, Incorporated, a corporation of
New York

Application April 14, 1938, Serial No. 202,083

4 Claims. (Cl. 2—269)

This invention relates to apparel, and has particular reference to the provision of apparel with means whereby the effective length of elements such as sleeves, waist bands and the like may be varied.

Generally speaking, the object of the invention is to embody in a sleeve, waist band or the like, a simple, practical, easily operable means to adjust the effective length thereof and to maintain the adjustment.

A special object of the invention is to provide an effective length adjusting means for apparel elements such as mentioned which means is effective to obtain various different definite and indicated effective length adjustments of the apparel elements.

Another special object of the invention is to provide an adjustment means for the purpose stated which is substantially invisible and which does not detract from the appearance of the apparel element in which it is embodied.

Another special object of the invention is to provide an adjustment means for the purpose stated which may readily and easily be embodied in apparel elements at small cost and which is thoroughly reliable and efficient in the performance of its function.

With the foregoing and other objects in view, which will become more fully apparent as the nature of the invention is better understood, the same consists in the novel combination and arrangement of features as will be hereinafter more fully described, illustrated in the accompanying drawing and defined in the appended claims.

In the accompanying drawing, wherein like characters of reference denote corresponding parts in the different views:

Figure 1 is a perspective view illustrating the embodiment of the invention in a shirt sleeve.

Figure 2 is an enlarged elevation of the construction illustrated in Fig. 1.

Figure 3 is a longitudinal section on the line 3—3 of Fig. 2; and

Figure 4 is a cross section on the line 4—4 of Fig. 2.

While the invention is illustrated in the drawing as embodied in a shirt sleeve, it will be understood that this is merely for convenience and for the purpose of illustrating one utility of the invention, and that the shirt sleeve, designated as 10, is representative of any other apparel element the effective length of which it is desired should be variable or adjustable.

In accordance with the invention, the sleeve

or equivalent apparel element 10 has formed therein at a suitable point a pair of slits 11, 11 which extend transversely relative to said element and are suitably spaced apart longitudinally thereof. Also in accordance with the invention, one element 12 of a snap fastener is secured in any suitable manner to the element 10 at the outer side thereof between and in line with the slits 11, 11; a tape 13 is provided at spaced points therealong with snap fastener elements 14 for cooperation with the snap fastener element 12; said tape is threaded through the slits 11, 11 so that its end portions are disposed at the inner side of the element 10 and a medial portion thereof overlies the outer face of said element between 15 said slits, and at least one end of said tape is fastened to the element 10 at a point suitably spaced longitudinally of said element 10 from the snap fastener element 12 as indicated at 15. The other end of the tape may be free or may be fastened with respect to the element 10 and, if fastened, it may be fastened to said element 10 at any suitable point. Preferably, it is fastened and preferably, too, for the sake of simplicity and convenience, it is fastened by the same means 20 which fastens the snap fastener element 12. Moreover, the length of the tape preferably is greater than the length of the element 10 between the end fastenings of said tape by an amount such that the portion of the tape adjacent to its second mentioned end always affords a loop 16 for finger engagement to facilitate adjustment of the effective length of the element 10.

Obviously, by drawing the tape 13 through the slits 11, 11 to cause the first mentioned end portion of the tape to approach the snap fastener element 12, the portion of the element 10 between the first mentioned end portion of the tape and said snap fastener element 12 will become pleated 35 or gathered and foreshortened, thereby reducing the effective length of said element 10, and by engaging any selected snap fastener element 14 with the snap fastener element 12, a desired foreshortened or reduced effective length adjustment 40 of the element may be maintained. In this connection it is preferred that the snap fastener elements 14 be spaced apart definite distances along the tape 13 and that said snap fastener elements 45 be provided with suitable means to indicate the different effective lengths of the element 10 which are obtained by engagement of the different snap fastener elements 14 with the snap fastener element 12. Thus, the obtaining of different defi- 50 55

nite effective length adjustments of the element 10 is facilitated.

Preferably a strip 17 is sewed to the element 10 at the inner side thereof to provide, in conjunction with said element 10, a pocket to contain the tape 13, but, as is apparent, the strip 17 is not essential and may be eliminated, if desired.

When the means comprising the invention is applied to a shirt sleeve, said means preferably is 10 applied at the outside of the sleeve where it is not affected by raising or lowering of the arm and where there is little or no likelihood of the sleeve being placed in sufficient tension to cause separation of the snap fastener elements 12, 14.

15 As will be apparent from the foregoing description considered in connection with the accompanying drawing, the device may readily and easily be embodied in apparel elements at small cost and is neat, easy to operate, substantially 20 invisible, does not detract from the appearance of the apparel element and, obviously, will efficiently perform its intended function.

Without further description it is thought that 25 the features and advantages of the invention will be readily apparent to those skilled in the art, and it will of course be understood that changes in the form, proportion and minor details of construction may be resorted to, without departing from the spirit of the invention and scope of the 30 appended claims.

I claim:

1. An apparel element having a pair of slits extending transversely thereof, a separable fastener element secured to said apparel element at

the outer side thereof between said slits, a flexible element extending through said slits and having its end portions disposed inwardly of said apparel element and its intermediate portion overlying the apparel element between said slits, one end of said flexible element being fastened to the apparel element at a point spaced longitudinally along the apparel element from said separable fastener element, and a series of separable fastener element carried by said flexible 10 element and spaced therealong for selective co-operation with said first mentioned separable fastener element.

2. An apparel element as set forth in claim 1 including a common securing means for the first 15 mentioned separable fastener element and the other end of the flexible element.

3. An apparel element as set forth in claim 1 in which the other end of the flexible element is fastened with respect to the apparel element and 20 in which the flexible element is longer than the length of the apparel element between the fastened ends of said flexible element by an amount such that a portion of the flexible element always is available as a loop for finger engagement to 25 facilitate gathering of the material of the apparel element along said flexible element.

4. An apparel element as set forth in claim 1 in which a strip is fastened to the apparel element at the inner side thereof and in cooperation with 30 said apparel element provides a pocket containing a major portion of the flexible element.

THOMAS R. ARDEN.
